Francis Gascoigne Lynde,

INVENTOR

By his Attorney, *Laurens Gascoigne*

UNITED STATES PATENT OFFICE.

FRANCIS GASCOIGNE LYNDE, OF BELVEDERE, ENGLAND.

MEANS FOR THE CONSTRUCTION OF CONCRETE SLABS, WALLS, AND OTHER STRUCTURES.

1,425,117.

Specification of Letters Patent. Patented Aug. 8, 1922.

Application filed July 15, 1919. Serial No. 311,049.

(GRANTED UNDER THE PROVISIONS OF THE ACT OF MARCH 3, 1921, 41 STAT. L., 1313.)

To all whom it may concern:

Be it known that I, FRANCIS GASCOIGNE LYNDE, subject of the King of Great Britain, and resident of The Eaves, Picardy Hill, Belvedere, Kent, England, have invented certain new and useful Improved Means for the Construction of Concrete Slabs, Walls, and Other Structures (for which I have filed application in England, January 4, 1918, Patent No. 120,825), of which the following is a specification.

This invention relates to the construction and connecting of concrete slabs of the kind in which the jointing is effected by means of grooves and dowels and of rods passed through loops or eyes formed by the projecting portions of reinforcing rods or bars and the joints enclosed by a filling of concrete said slabs being suitable for the erection of structures such as walls of buildings, sea walls, harbour works, piers of bridges, sunk foundations, retaining walls, ships, pontoons, tanks, sanitary buildings, hospitals, barracks, farm buildings, outhouses, cottages and the like.

The chief objects are to provide slabs or members constructed of concrete adapted for assemblage and connection in an efficacious and expeditious manner and which when erected to form the desired structure shall ensure great strength and stability thereto.

According to this invention the horizontal junctions of the concrete slabs are arranged in staggered relation and strengthened by grooves and dowels. Additional securing devices are provided at the vertical junctions by passing rods or wires transversely through the slabs or members and twisting or entwining their ends.

Slabs or members joined or connected in the manner above described may be arranged to constitute walls and may be arranged in plain or straight formation or they may be zig-zag. They may moreover be arranged so as to form cells for the reception of concrete or other heavy material for affording stability or to constitute watertight compartments in ships or pontoons stalls in farm buildings or apartments in cottage and other similar structures.

In order that the invention may be clearly understood and carried into effect same will now be more fully described with reference to the accompanying drawings in which:—

Figure 1 is an elevation of a portion of a wall constructed in accordance with the improved method. 55

Figure 2 is a horizontal section thereof showing the method of completing the vertical joint and combining right-angled walls so as to form cells chambers or apartments. 60

Figure 3 is a view similar to Figure 2 showing a zig-zag wall and walls to form cells chambers or apartments.

Figure 4 is a fragmentary view in elevation drawn to a larger scale showing three wall structures and the method of joining or connecting them together vertically. 65

Figures 5 and 6 are views also drawn to a larger scale in transverse section showing respectively a right-angled junction of slabs or members as in Figures 1 and 2 and an obtuse angled junction of slabs or members as in Figures 3 and 4. 70

The formed concrete slabs 1 are erected to form a wall for example by being placed edgeways upon each other the horizontal junctions being effected by means of grooves 2 (Figure 4) and dowel pins 3. The arrangement is such that the said junctions of the built-up slabs or members 1 of one vertical series break joint or are in staggered relationship with the junctions of adjoining vertical series of slabs or members as clearly shown in Figure 1 the several junctions being indicated at 4. 80

By the expression "staggered relation" I do not intend to convey merely that the horizontal junctions or joints between the slabs composing one vertical series are staggered relatively to the horizontal junctions or joints between the slabs composing adjacent vertical series but also that the horizontal joints in alternate vertical series of slabs are staggered relatively to each other as by this means each of the individual slabs except those composing the lowermost and uppermost portions of the structure is supported and stiffened by the maximum number of slabs. By arranging the horizontal junctions in such a manner a very firm and strong structure is ensured and the slabs or members being ready prepared the erection is capable of accomplishment with great expedition. The slabs or members may be reinforced with the well known expanded metal or wire netting as indicated in broken lines in Figure 4. For effecting the vertical junction of the slabs 95

100

105

or series of slabs the latter are provided with steel or other metal rods or wires 5 embedded therein and having projecting portions looped as at 6 and tied or laced together by metal bars 7 threaded or passed through the said loops. The contiguous portions of the expanded metal reinforcement which project from the ends of the slabs may also be engaged by threading the aforesaid bars 7 through overlapping meshings of the said reinforcement and thereby tying or interlocking them together. The junctions may be further secured by means of rods or wires 8 (see particularly enlarged views Figures 5 and 6) passed transversely through the material of the slabs or members and having their ends twisted or entwined as at 9. The interstices or spaces in the joint are filled with concrete as shown at 10 and the vertical junction effectually secured, the rods, bars and interlacing being thereby concealed and the metal protected from corrosion.

In Figures 1, 2 and 5 a flat wall is shown having right-angled walls 11 joined thereto. A method of effecting the junction at the angle of these walls is clearly shown in the large transverse section Figure 5 in which the walls comprising the slabs 1 are joined with the walls 11 by the above described system of interlacing and threading the plain junctions being indicated at 12 Figure 2. All the metal work pertaining to the unions is enclosed or concealed by a suitable concrete covering.

When the walls are required to be zig-zag in transverse section as at 13 in Figure 3 the apices or angles are joined in a manner similar to that already described with reference to the plain or flat junctions the metal work of the union being concealed by concrete 14. The branch walls 11 are connected with the zig-zag wall by the interlacing or interlocking also hereinbefore described, see particularly the enlarged view Figure 6 which represents the obtuse-angled union or junction shown at 15 in Figure 3.

In Figure 5 the dotted lines extending from the lower part of the figure indicate the manner of extension by continuing walls 11 upon either side of walls 1. The method of effecting their union will however be clearly understood without further description.

It will be apparent that the method of joining concrete slabs such as above described and shown in the drawings will be found eminently suitable for employment in connection with flooring or roofing same presenting a perfectly water tight structure capable of use in a flat or zig-zag form. Assuming the latter to be desired one may regard the slab portions 13 (Figure 3) as representing the roofing and the portions 11 two of the walls supporting the same.

By the employment of the herein described

readily prepared slabs or blocks a structure of any desired form may be quickly erected as owing to the avoidance of the delay incidental to the time required for large masses of concrete to set or harden the completion of the work of construction is rendered very expeditious.

The invention readily lends itself to the erection of structures of the cellular type the cells serving as water tight compartments or for the reception of heavy material to increase the stability of the structure or for rooms or apartments.

I claim:

1. Concrete slab walls and other structures comprising slabs, rods therein, looped ends on said rods, vertical rods passing through said looped ends, and extending between the junctions of the slabs, grooves in the horizontal edges of said slabs, dowels passing through said horizontal edges and engaging said slabs, and additional metal securing means at the vertical junctions of the slabs the slabs being arranged so that the horizontal junctions in any vertical series of slabs are in staggered relation to the junctions in the adjoining vertical series of slabs.

2. Concrete slab walls and other structures comprising slabs, rods, therein looped ends on said rods, vertical rods passing through said looped ends, grooves in the horizontal edges of said slabs, dowels passing through said horizontal edges and engaging said slabs, and metal securing means for passing through said slabs near the ends thereof, said slabs being arranged so that the horizontal junctions in any vertical series of slabs are in staggered relation to the junctions in alternate vertical series.

3. Concrete slab walls and other structures comprising slabs, rods therein, looped ends on said rods, vertical rods passing through said looped ends, grooves in the horizontal edges of said slabs, dowels passing through said horizontal edges and engaging said slabs, metal securing means engaging the slabs at the vertical junctions thereof, and a filling of concrete at the vertical junctions of said slabs.

4. Concrete slab walls and other structures comprising slabs, rods therein, looped ends on said rods, vertical rods passing through said looped ends, a filling of concrete, grooves in the horizontal edges of said slabs, dowels passing through said horizontal edges and engaging said slabs, metal securing means engaging the slabs at the vertical junctions thereof and a filling of concrete at the vertical junctions of said slabs and surrounding said metal securing means.

Signed at London, England, this 23rd day of May A. D. 1919.

FRANCIS GASCOIGNE LYNDE.
